Charles Leigh Paulus

By Robert W. Young, Attest.

UNITED STATES PATENT OFFICE.

HERBERT O. RUSSELL, OF DETROIT, MICHIGAN, AND CHARLES LEIGH PAULUS, OF DAYTON, OHIO.

AUTOMATIC COCKING ATTACHMENT FOR MACHINE GUNS.

Application filed April 18, 1922. Serial No. 555,411.

To all whom it may concern:

Be it known that we, HERBERT O. RUSSELL and CHARLES LEIGH PAULUS, citizens of the United States, residing, respectively, at Detroit and Dayton, in the counties of Wayne and Montgomery and States of Michigan and Ohio, have invented certain new and useful Improvements in Automatic Cocking Attachments for Machine Guns, of which the following is a specification.

This invention relates to a cocking attachment for machine guns. The object of the invention is to provide for automatically re-cocking the machine upon failure to fire and when therefore there is no recoil action. The mechanism herein described is shown as designed to automatically cock the gun. It does not hamper the forward movement of the bolt which is accomplished only by the bolt actuating spring. By functioning in this way the mechanism will allow machine guns to fire ammunition which would otherwise be worthless, due to the fact that the machine gun upon taking a single dead shell would stop its fire.

The invention consists in the novel construction, combination and arrangement herein fully described, illustrated and claimed.

30 In the accompanying drawings:

Figure 1 is a longitudinal section through the automatic cocking attachment shown applied to a machine gun.

Figure 2 is an end view thereof.

35 The construction of the automatic cocking attachment, in the preferred embodiment thereof, comprises a mounting bracket 1 which is used to mount the mechanism on the machine gun, said mounting bracket having fixed thereon a mounting tube 2 which forms a bearing guide for an outer tube 3, the latter being carried to the rear upon the recoil stroke of the bolt of the gun and held in place by a catch 4. A cocking 40 rod 5 which is normally free to move back and forth with the bolt is attached to a stud or cocking handle 6 projecting laterally from the bolt. Upon failure of the gun to fire, a locking dog 7 will be allowed to move

slowly out of locking position at a speed 50 governed by an air cylinder 8 in which said dog is mounted, the dog projecting from and being carried by a piston 8' movable in the cylinder 8 the movement thereof being resisted by a coiled expansion spring 10. The 55 dog 7 is moved out of locking position by a camming action of the plunger hereinafter referred to. The bolt 6 being in its forward position at that time, allows the spring pressed plunger 9 under the pressure of its 60 actuating spring 11 to carry the bolt to the rear, thereby extracting the dud shell from the chamber. Upon reaching the rear end of its stroke, the plunger 9 will trip the catch 4, allowing the outer tube 3 to travel 65 free with the forward movement of the bolt 6. This allows the plunger 9 to catch behind the dog 7. The next recoil stroke of the gun cocks the mechanism and allows the same to stand ready to again automatically 70 cock the gun upon the next failure of the gun to fire.

Having thus described our invention, we claim:

1. The combination with the bolt of a machine gun, of automatic cocking means embodying a normally free cocking rod connected to and operating in unison with the bolt, a spring plunger for thrusting said rod rearwardly upon failure of the gun to fire, 80 and a catch for normally holding said spring in check but adapted to automatically release the plunger in case of non-fire.

2. The combination with the bolt of a machine gun, of automatic cocking means embodying a normally free cocking rod connected to and operating in unison with the bolt, a spring plunger for thrusting said rod rearwardly upon failure of the gun to fire, a detent for retaining the plunger spring in 90 operative position until the bolt is fully retracted after a misfire, and a catch for normally holding said plunger in check but adapted to automatically release the plunger in case of non-fire.

3. The combination with the bolt of a machine gun, of automatic cocking means embodying a normally free cocking rod con-

nected to and operating in unison with the bolt, a spring plunger for thrusting said rod rearwardly upon failure of the gun to fire, and a catch for normally holding said spring in check but adapted to automatically release the plunger in case of non-fire, and a detent being tripped by the plunger, permitting the cocking rod and the spring casing to be again carried forward by the bolt. In testimony whereof we affix our signatures.

10
HERBERT O. RUSSELL.
CHARLES LEIGH PAULUS.
